US0D1096866S

(12) **United States Design Patent** (10) **Patent No.:** **US D1,096,866 S**
(45) **Date of Patent:** **** Oct. 7, 2025**

(54) **AUTOMATED, CLIMATE-CONTROLLED PRODUCT STORAGE UNIT**

(71) Applicant: **TRUMED SYSTEMS, INC.**, San Diego, CA (US)

(72) Inventors: **Scott Edward Shultz**, San Diego, CA (US); **Kenneth A. Regas**, Poway, CA (US); **Javier A. Escobedo**, San Diego, CA (US); **Brian Mikael Andersen**, San Diego, CA (US)

(73) Assignee: **TruMed Systems, INC.**, San Diego, CA (US)

(**) Term: **15 Years**

(21) Appl. No.: **29/971,232**

(22) Filed: **Nov. 1, 2024**

(57) **CLAIM**

An ornamental design for an automated, climate-controlled product storage unit, substantially as shown and described.

DESCRIPTION

FIG. 1 is a perspective view of an automated, climate-controlled product storage unit with access panel, showing our new design;

FIG. 2 is a top plan view thereof;

FIG. 3 is a perspective view of a second embodiment of an automated, climate-controlled product storage unit with access panel, showing our new design;

FIG. 4 is a top plan view thereof;

FIG. 5 is a perspective view of a third embodiment of an automated, climate-controlled product storage unit with access panel, showing our new design;

FIG. 6 is a top plan view thereof;

FIG. 7 is a perspective view of a fourth embodiment of an automated, climate-controlled product storage unit with access panel, showing our new design;

FIG. 8 is a top plan view thereof;

FIG. 9 is a perspective view of a fifth embodiment of an automated, climate-controlled product storage unit with access panel, showing our new design; and,

FIG. 10 is a top plan view thereof.

1 Claim, 5 Drawing Sheets
